PLAYGROUND FIREMAN SLIDE

Robert S. Wormser, Mexico, Pa., assignor to The Mexico
Forge, Inc., Mexico, Pa., a corporation of Pennsyl-
vania

Application September 30, 1958, Serial No. 52,820

Term of patent 14 years

(Cl. D34—5)

FIG. I.

FIG.4.

FIG.5.

Fig. 1 is a perspective view of a playground fireman slide according to my new design.

Fig. 2 is a front elevation of said slide.

Fig. 3 is a right side view of the slide.

Fig. 4 is a rear view of the slide.

Fig. 5 is a section along line 5—5 of Fig. 2.

I claim:

The ornamental design for a playground fireman slide, substantially as shown.
